STACK CLAMP

Jess G. Galik, Bayside, N. Y., assignor to American Seal-Kap Corporation of Delaware, Wilmington, Del., a corporation of Delaware

Application May 5, 1950, Serial No. 160,370

1 Claim. (Cl. 226—88.1)

1 This invention relates to cap dispensing and applying machines of the type shown in co-pending application Serial No. 740,162, filed April 8, 1947, now Patent No. 2,563,654, dated August 7, 1951, which is adapted to dispense and apply to milk bottles preformed caps having a central depressed diaphragm adapted to seat on the internal ledge of the bottle, a raised U-shaped pouring rim housing adapted to extend over the pouring rim of the bottle, and a flaring outer skirt which is adapted to be contracted and sealed around the neck of the bottle. A separate disc is usually seated against the depressed diaphragm.

The machine in general includes picker mechanism for picking individual caps successively from a stack of nested caps, means feeding a procession of such caps through a heating zone wherein they are conditioned for sealing, means applying the conditioned caps to the mouths of a procession of filled bottles, and means contracting the cap skirts for sealing about the necks of the bottles.

In the stack the nested caps advance with their tops foremost and with their flared skirts trailing. Hence the cupped portion comprising the pouring lip housing and central depressed diaphragm must be contacted by the picker means. The picker means includes a reciprocating plunger which engages the foremost cap and withdraws the same from the stack. In so doing the picker head strikes or pushes the cap and in certain instances produces an impact which is transferred through the stack to the trailing cap or caps and may cause them to become displaced in the chute to an extent to interfere with the proper nesting of a subsequent supply of caps which is fed onto the end of the stack.

It is an object of the present invention to provide a novel and improved means to prevent such displacement of the caps by the impact of the picker.

Various other objects and advantages will be apparent as the nature of the invention is more fully disclosed.

In accordance with the present invention a retractile clamp is provided in a position to engage the stack of caps at a substantial distance from the forward end of the stack. The clamp is actuated in synchronism with the picker plunger and is arranged to contact and clamp the stack during the time when the picker head is in contact with the foremost cap in the stack. In one embodiment the clamp is actuated during the forward stroke of the picker plunger and is released during the return stroke of the plunger.

2 The clamp holds a portion of the stack against movement and prevents the displacement of the foremost cap by the picker from being transferred along the stack to the trailing cap or caps. Hence the trailing caps remain in proper nested position to receive a further supply of caps without interruption of the nested stack.

The nature of the invention will be better understood by referring to the following description, taken in connection with the accompanying drawings in which a specific embodiment thereof has been set forth for purposes of illustration.

In the drawings:

Fig. 1 is a longitudinal section through a picker and stack embodying the present invention with the control mechanism shown diagrammatically;

Fig. 2 is an enlarged section taken on the line 2—2 of Fig. 1; and

Fig. 3 is a top plan view of the mechanism shown in Fig. 2.

Referring to the drawings more in detail, a stack of caps 10 are held within a magazine 11 by a ring 12 which engages the depending skirt 13 of the lowermost cap and holds the caps in position for successive withdrawal from the stack by the picker means.

The picker means comprises a suction head 20, adapted to engage and withdraw the lowermost cap from the stack as described in said co-pending application Serial No. 740,162.

The head 20 is carried by a plunger 21 actuated by a piston rod 22 which is slidable through a bushing 23 in the head 24 of a cylinder 25 and is attached to a piston 26 slidable in said cylinder. The cylinder 25 is closed by heads 24 and 27. The heads 24 and 27 have axial recesses 30 and 31 having a small clearance with a boss 32 on the piston rod 22 and with a plunger 33 attached to the piston 26 respectively. Bores 34 and 35 extend through the heads 24 and 27 to register with the axial recesses 30 and 31 and communicate respectively with pipes 36 and 37 by which the fluid pressure in the two ends of the cylinder 25 is controlled.

The pipes 36 and 37 are shown as leading to a four-way valve 38 having a vent pipe 40 open to the atmosphere and having a suction pipe 41 connected to a suction pump 42. The four-way valve 38 is actuated by a solenoid 43 which is connected by leads 44 to a suitable control such as a bottle-actuated switch.

The magazine 11 and cylinder 25 are supported on a frame 45 having a chute 46 through which the caps are dropped by the picker head 20. A turret 47 having a plurality of cap stacks 50 is mounted for rotation on the frame 45 and is

driven by a worm 51 cooperating with a gear 52 on a shaft 53 carrying the turret. Suitable means is provided to index the turret when the stack 50 which is in registration with the magazine 11 is exhausted, so as to bring a fresh stack into registration therewith. The fresh stack then slides downwardly until it joins and nests with the stack 10 in the magazine 11 to form a continuous stack as shown in Fig. 1.

The parts of the machine so far referred to are shown more in detail in the co-pending application above mentioned and only so much thereof has been shown herein as is necessary for understanding of the present invention.

This invention provides a clamp arm 55 (Figs. 2 and 3) pivoted at one end to a pin 56 attached to the frame 45 and having at its free end an arcuate clamp 57 lined by a soft liner 58, such as rubber, and shaped and positioned to engage the skirts 13 of the stack 10 at a point on the magazine 11 remote from the leading end of the stack, but in advance of the trailing end of the magazine.

The clamp arm 55 is actuated by a rod 60 pivoted thereto by a pin 61 having sufficient play to allow for the slightly arcuate movement of the arm. The rod 60 extends through a bushing 62 in the head 63 of a cylinder 64. The head 63 is attached to the frame 45 by a threaded extension 65 on the head 63 and a lock nut 66. The cylinder 64 is closed by a second head 67.

The rod 60 is pinned to a piston 68 sliding in the cylinder 64. The heads 63 and 67 are formed with ducts 70 and 71 communicating with the cylinder above and below the piston 68, and connected by pipes 72 and 73 to the pipes 37 and 36 respectively.

An oil pipe 74, connected to a grease coupling 75 attached to the frame 45 supplies lubricant to the cylinder walls.

In the operation of this device, when suction is supplied to the pipe 36, the piston 26 is drawn to the forward end of the cylinder 25 and the plunger 21 is advanced to bring the head 20 into contact with the lowermost cap in the stack 10. The solenoid actuated valve 38 is spring-biased in such a direction that when the solenoid is deenergized suction is applied to the pipe 36 and the pipe 37 is vented to the atmosphere through the vent 40. Hence the piston and the plunger are normally maintained in their advanced position. When a bottle, in advancing around the filler closes a switch to energize the solenoid 43, the position of the four-way valve is reversed, admitting suction to the line 37 and 55 venting the line 36 through the port 49. This causes the piston 26 and the plunger 21 to be retracted. As the plunger is retracted the lowermost cap is removed from the stack by the head 20 and allowed to drop onto the cap chute 46.

When suction is supplied to the cylinder 26 by the pipe 36 to advance the picker mechanism, suction is also supplied to the bottom of the cylinder 64 by the pipe 73, thereby lowering the piston 68 and drawing the clamp 57 against the caps in the stack 10. The travel of the piston 68 and the volume of the chamber in the cylinder

64 are less than the travel of the piston 26 and the volume of the chamber in the cylinder 25. Hence the clamp 57 is set against the caps in the stack 10 before the picker head 20 engages the lowermost cap and prevents any displacement of the caps in the stack by the impact or movement of the picker head.

When suction is applied to the pipe 37 to retract the picker head, suction is also supplied to the chamber in the cylinder 64 above the piston 68 to raise the clamp 57 and release the stack to feed downwardly in the usual manner. The action is such that the clamp is raised before the picker reaches the limit of its stroke and preferably at the initial portion of its stroke so as to allow sufficient time for the stack to advance before the next cycle of operation.

It has been found that this device assures the proper and uniform feed of the caps and retains the trailing caps in the stack in their proper position to receive the fresh supply from the stack 50 of the turret when one stack 50 is exhausted and the turret is indexed to bring another stack 50 into feeding position as set forth more in detail in said co-pending application.

Although a specific embodiment of the invention has been shown for purposes of illustration, it is to be understood that the invention may be applied to various uses and that changes and adaptations may be made therein as will be readily apparent to a person skilled in the art.

What is claimed is:

A machine for dispensing caps from a stack of nested caps, comprising a magazine adapted to contain a stack of said caps and to feed the stack forwardly as caps are removed from the forward end thereof, picker mechanism, fluid pressure means to advance and retract said picker mechanism for engaging and withdrawing the leading cap from said stack, a stack clamp positioned to clamp an intermediate portion of said stack, fluid pressure means to set and release said clamp for alternately clamping and releasing said stack and means actuating both of said fluid pressure means in unison for setting said clamp during the advance of said picker mechanism and releasing said clamp during the retraction of said picker mechanism, said last fluid pressure means being quicker acting than said first fluid pressure means, whereby the clamp is set before the picker mechanism contacts said stack and is released when the leading cap is withdrawn from said stack.

JESS G. GALIK.
